WILLIAM F. RODIN AND ALEXANDER HURAL, OF LOS ANGELES, CALIFORNIA

DENTAL FLASK

Application filed December 17, 1929. Serial No. 414,802.

Our invention relates to dental curing and vulcanizing flasks, and has for its primary object the provision of means for automatically compensating for expansion and contraction of the vulcanizable plate-forming material during the vulcanizing process, whereby to insure accuracy in the formation of plates, which said means is structurally qualified so as to function to pack or condense the molten mass of material in the mold cavity and thereby maximize the density of the material and render same free from voids and imperfections that, if left in the finished plate, would result in a weakened plate structure.

In the work of supplying a dental flask with molten plate-forming material, such as vulcanizable rubber, it frequently happens that either too much or too little of the material is supplied the mold. If the flask is over-supplied, it follows that the mold is liable to fracture when subjected to the customary steps of a vulcanizing treatment, and that, incident to the action of expansion and contraction of the material, the structure of the denture is sometimes so disorganized that same is made wholly unfit for the purpose intended. When material in an insufficient quantity is placed in the mold, it consequently results that the teeth to be cast in the plate find insufficient anchorage therein and same can be easily separated from their sockets.

We have designed certain new and novel means whereby conditions within the flask are always discernible from a point exteriorly of the flask, which said means automatically functions to exert pressure upon the plate-forming material and to closely pack same within the mold cavity, while being free to permit of movement of the material relatively to the cavity incident to the action of expanding and contracting temperatures to which the material is subjected. The means which we have employed is self-compensating to all internal conditions of the flask and it is further designed so that, and should external

examination of the flask indicate that the mold cavity contains an insufficient quantity of material, it may be conveniently supplied or charged with a further quantity by an operation conducted entirely externally of the flask, and while the sections of the latter are under pressure by the action of any customary press. Again, it is a further aim of the invention to provide means whereby, should the mold cavity be over-supplied with plate-forming material, same may be bled to the outside of the flask. In other words, a part of the whole mass originally supplied the mold cavity can be quickly evacuated from the cavity and in a way that will enable a skilled operator, or even a laboratory assistant, to ascertain when the cavity is properly supplied in a way that will satisfactorily meet those requirements for a strong, durable plate structure and an adequate anchorage of the teeth therein.

Our invention is used preferably in conjunction with a flask formed of separable sections, and we have provided in our assembly of instrumentalities means for preventing the plastic material within the flask from escaping from the flask by way of the joinder between the flask sections. In other words, we have employed herein means for satisfactorily establishing a perfect seal at the point between the flask sections so as to prevent external pressures from entering the flask while avoiding an escape of materials within the flask by the action of internal pressures, all of which said pressures are due to actions of heats during the vulcanizing treatments.

Our invention aims further to provide a novel organization of parts including means that will enable the flask sections to be either set up or taken apart with ease and dispatch, and means for holding all of the parts in assembly and firmly pressed together.

In the accompanying drawings, Figure 1 is a perspective view of the flask showing the same fully assembled;

Figure 2 is a perspective view showing the component parts of the flask disassembled;

Figure 3 is a vertical section through the flask on line 3—3 of Figure 1 showing the initial position of the pressure exerting means with respect to the mold cavity.

Figure 4 is a horizontal section on an enlarged scale through a central portion of the flask.

Except for one feature of importance, which we will stress hereinafter, we make no claim to the steps of the molding method employed. The customary plastic material used in connection with dental flasks is applied within the flask sections in the usual well known manner. The mold is arranged within the flask also in the usual manner, so that the wax carried thereby will function to produce a mold cavity in the plaster of Paris mass contained in the flask. There is to be considered, however, in connection with this customary method of arranging a mold within plastic matter in the flask, the fact that our mold sections are so proportioned and otherwise designed that the mold cavity will occupy a position with respect to the flask sections as will enable the same to be operatively correlated to the means for exerting pressure upon the molten plate-forming material. This relationship of the parts will be described in proper detail as the description proceeds.

We employ a flask which comprises an upper annular body 10 having vertical lugs 10', a mating lower annular body 11 having a vertical recess 11', and recesses 11²—11², an intermediate annular gasket 12 having recesses 12', an imperforate top 13 having recesses 13', and an imperforate bottom or base 14 having vertical lugs 14', the latter adapted to fit in the mating vertically aligned recesses 12' and 11². The lugs 10' are adapted to fit in the aforementioned recesses 13'. All of the parts just above mentioned are relatively of the same external and internal diameters so that the flask presents when set up a cylindrical structure whose external walls are perpendicular. The said parts are adapted to be built up one upon the other so as to come in close mating contact at the joiners between the respective parts. The said parts are also preferably formed of brass and, as illustrated in Figure 2, the aforementioned gasket 12 is open at one side as at 15. The confronting ends of the gasket are formed with alined recesses 16, the purpose of which will be explained hereinafter.

The bottom or base 14 is provided in its peripheral edges with vertical recesses 17. The lower section 11 is formed with vertical recesses 18 which coincide with the recesses 17. The gasket 12 is formed with recesses 19 adapted to coincide with the recesses 18. The upper section 10 is formed with recesses 20 to coincide with the recesses

19, and the top 13 is formed with recesses 21 to coincide with the recesses 20. We have now described an arrangement of the respective flask parts whereby the external recesses of these parts may be brought into coinciding relationship with each other so as to allow for the accommodation therein of equidistantly spaced clamping arms 22 of which there are preferably three. These arms are formed with angularly extending flanges 23 at their lower ends adapted to engage under the bottom section 14 of the flask. The upper ends of these arms are looped about pintles 24 which are carried in loops 25 formed upon the outwardly extending extensions 26 of a clamp head 27. The arms 22 are constructed of rigid material, preferably metal, and the clamp head 27 is constructed of resilient metal, so that the extensions 26 of the latter may be put under some elastic stress. The clamp head 27 is formed at its center with a threaded aperture 28 adapted to receive an externally threaded adjusting plug 29. Reference should now be made to Figure 1 of the drawings, wherein it will be observed that the upper extremities of the arms 22 extend above the top section 14 of the flask. Also it will be observed that the plug 29 is freely adjustable in a vertical direction in its co-acting opening 28 in the clamp head 27. Likewise is it observed that the plug may be adjusted in the opening 28 so that the lower face of the plug can be firmly pressed against the flat upper face of the flask section 13. The plug 29 is formed with a vertical wrench cavity 30 in order that the plug can be turned either to the left when effecting a clamping action between the flask parts or to the right when it is desired to knock down the flask.

The gasket 12 projects into the flask chamber and same is formed with a vertical rib 31 which is spaced apart from the inner walls of the flask section 10. This allows for the flowing of plaster over the rib so as to produce an effective plastic key or seal at the joint between the gasket and the section 10 of the flask. The upper face of the gasket falls in horizontal alinement with the joint between the two plastic masses contained in the two sections 10 and 11 of the flask, and these masses may be isolated from each other through the medium of a suitable varnish of the type customarily employed in dental flasks of the character before us. This prevents escape of the plastic material within the flask, and it also seals the flask against the action of external pressure when the flask is submerged in hot water during the time of melting the wax carried by the mold.

The base 14 of the mold is formed with a vertical saddle 32 having a substantially semi-circular recess 33 adapted to coincide

with the recess 34 in the flask section 10. The recess 33 forms lugs 35 at opposite sides thereof on the saddle 32 and these lugs are received in recesses 35^a formed in the section 10. They are also received in recesses 35^b in the gasket 12. The recesses 33 and 34 combine to produce or define a circular receptor for an open-ended cylindrical barrel 36. This barrel is formed at its sides with pins 37 adapted to enter the respective recesses 16 in the confronting faces of the gasket 12. The barrel is of a length whereby it projects well into the flask, as will be seen on reference to Figure 4 of the drawings, so that its inner end is in horizontal alinement with the plate-forming cavity A. Within the barrel is a combined pressure exerting or compressing means and vent means B which comprises a body having sections 38 and 39 of respectively different external diameters, each section being a cylinder of suitable length. The said body has a bore 41 which threadedly accommodates a screw plug 41' which normally serves to close said bore. Between the outer wall of the barrel 36 and the shoulder 42 of the combined pressure exerting and vent means is a spring 43 which functions to normally urge said means B in the direction of the mold cavity A. A stop pin 45 operates in the groove 46 in the means B to limit movements of the latter. In this manner, it follows that said means B cannot be entirely withdrawn from said barrel 38 either by action of the spring 43 or by the action of pressure created within the flask. At this point, it is stated that the pressure exerting and vent means acts plunger-like and same is free for pulsating movement in the barrel in order to accommodate itself to the action of internal pressures. It is, therefore, self-compensating to all pressure actions that are customarily created in flasks of this nature during vulcanizing of the plate-forming material.

Having described the essential structural characteristics of the flask, a brief description of its mode of functioning will be as follows: Plaster of Paris is placed in the lower flask section 11. The plate-forming mold A' is associated with the plastic material. The flask sections are then superposed relatively and the section 10 filled with plaster in the regular manner. The plaster within the flask is then permitted to harden, after which the flask is subjected to the action of hot water to melt the wax carried by the mold and thereby produce a plate forming cavity within the plastic mass within the flask when the wax is melted out. By isolating the plastic mass contained in the section 11 from the mass contained in the section 10, it follows that after the wax melting step has been conducted the two masses may be freely separated and vulcanizable material, such as rubber or other well known equivalent thereof,

applied within the mold cavity thus produced. When arranging wax in the flask, a slug forming portion C is interposed between the inner end of the means B and the mold A'. During the process of melting the wax so as to produce a mold cavity in the plaster contained in the flask, it follows that the portion C will also be melted so as to leave a void between the inner end of the means B and the cavity. The vulcanizable material within the flask is now ready to be subjected to the customary vulcanizing treatment. Due to the characterizing features of the pressure exerting and vent means B, it manifestly follows that when the flask is subjected to the action of vulcanizing heats and the plate-forming material is thereby made to respectively expand and contract, the slug C, which normally acted as a barrier, has now been melted away and the said means B is free for reciprocal movement. It is self-compensating to all capacity charges contained in the mold cavity, and should it happen that the mold cavity contains less material than is suitable for a practical manufacturer of a dental plate, this may be ascertained by simply withdrawing the screw 41' from said means B, at which time it will be found that no molten plate-forming material will find egress from the mold cavity by way of the bore 41 in said means B. This would go to indicate that the mold cavity contains an insufficient quantity of vulcanizable material and the operator would then inject into the cavity by way of said bore such quantity as may prove ample for the occasion. This operation may be continued from time to time until no vulcanizable material finds escape to the outside by way of said bore. Here it should be noted that the screw plug 41 is not left permanently disconnected from said means B after an inspection of the internal workings of the flask. It is intended that on each inspection the screw be again driven to its home. Conversely, it follows that when the screw is removed should too much material be contained in the mold cavity, the excess is free to flow therefrom, where it will pass off to the external part of the flask by way of the bore in said means B. We have accordingly devised ways and means whereby an operator can determine accurately the internal workings of the flask during the entire vulcanizing treatment. The plunger-like pressure-exerting and vent means B operates automatically and exerts a normal pressure against the molten plate-forming material. In this manner, and when the mold is insufficiently packed, the vulcanizable material in the plate-forming cavity of the mold may be supplied with a further quantity of material. The means described herein is reliable in action and is self-compensating to all ordinary heat pressures, and by permitting the excess of material to seek its escape from the mold

forming cavity, we nicely guard against resulting fractures of the mold or a displacement of the teeth during the vulcanizing operation. We are able to determine upon external inspection of the mold whether the mold cavity contains just the proper quantity of material or whether the quantity is too meagre to permit firm anchorage of the teeth in the plate-forming material, and we have further provided for a close condensing of the material so as to free the same of voids that would weaken the commercial or finished plate.

In order that the plug 29 may be operated to effect a maximum clamping action and at the same time be capable of easy adjustment with little created friction, we provide same with an annular series of anti-friction bodies 29' which are free to ride against the flat face 30 of the aforementioned flask section 13.

We claim as our invention:

1. A flask having an inwardly-extending barrel, a yieldable plunger carried by the barrel and extending into the flask, the plunger having a bore opening into the flask, and removable means for normally sealing the bore at one end.

2. A flask including a plurality of mating flask sections superposed with respect to each other, a gasket removably interposed between said sections and having an annular rib occupying a position within the flask and in spaced relation to the inner surface of one of said sections so that plaster contained in the flask will flow over the rib and onto the gasket at a point between said mating sections, closing means for the flask, and means for clamping the closing means and the flask sections together.

3. A dental flask including a plurality of mating flask sections, means for clamping the sections together, a yieldable plunger carried by one section and having a bore extending from a point at the exterior of the flask to a point interiorly thereof, and closing means for said bore.

4. A dental flask having a bore between its upper and lower ends, the said bore extending from a point at the exterior of the flask to a point interiorly thereof, a plunger operating in the bore, means for normally urging the plunger in one direction, the plunger having a bore therein, and means removable from the bore of said plunger and serving to normally close same against the escape of material from the flask.

5. A sealing gasket for dental flasks comprising an annular body adapted to be interposed between two flask sections, a cylinder carried by the gasket and having an open end adapted to be extended into a flask when the gasket is operatively related to said flask sections, and a yieldable plunger operating in said cylinder.

6. A sealing gasket for dental flasks comprising an annular body adapted to be interposed between two flask sections, a cylinder carried by the gasket and having an open end adapted to be extended into a flask when the gasket is operatively related to said flask sections, a yieldable plunger operating in said cylinder, the plunger having a threaded bore extending therethrough, and a closing screw normally closing said bore.
